UNITED STATES PATENT OFFICE.

EMANUEL W. SWEIGARD, OF CHICAGO, ILLINOIS.

COMBINATION-TOOL FOR BICYCLES.

SPECIFICATION forming part of Letters Patent No. 605,453, dated June 7, 1898.

Application filed March 20, 1896. Renewed January 31, 1898. Serial No. 668,672. (No model.)

To all whom it may concern:

Be it known that I, EMANUEL W. SWEIGARD, a citizen of the United States of America, residing at Chicago, in the county of Cook and State of Illinois, have invented certain new and useful Improvements in Combination-Tools for Bicycles, of which the following is a specification.

My invention relates to certain improvements in a combination-tool, the object being to provide a tool, such as a pneumatic pump, which shall itself be so constructed as to contain supplementary tools used upon a bicycle and the like. To such end it consists in providing the piston of a pneumatic pump, such as are used for inflating pneumatic tires, with chambers adapted to receive supplementary tools, the novel features of which will appear from the following specification and the essential portions particularly pointed out in the appended claims.

The invention is fully described in this specification and illustrated in the accompanying drawings, in which—

Figure 1 is a lateral perspective view of a tool in its preferred form. Fig. 2 is a view partly in side elevation and partly in section, the section being taken through the casing of the pump. Fig. 3 is a perspective view of one of the supplementary tools. Fig. 4 is a detail cross-section in line 4-4 of Fig. 2. Fig. 5 is a horizontal longitudinal section in line 5-5 of Fig. 2, and Fig. 6 is a detail perspective view of the piston-head used in connection with the pump.

In the views, A is the casing of a pneumatic pump, flat and approximately rectangular in cross-section in order that it may be conveniently carried in the pocket. One end of the casing is provided with a stationary head a, upon which is formed a small nipple a', by which the pump may be connected with the pneumatic tire of a bicycle by means of the ordinary tube used in connection with pumps of this class. The head is also preferably provided with a bail or loop a'', adapted for the attachment of a chain. The cylinder is open to receive a longitudinally-sliding piston.

The piston is seen at B and as shown consists of two parallel members b b', forming a convenient grasp when operating the pump. The members b b' are at one end connected

by a transverse member b'', which forms the piston-head. The piston-head is formed to conform to the shape of the casing and provided with a suitable packing b'', secured in place by a plate b', which is placed upon the outer face of the packing and screwed to the head b'', clamping the packing firmly between it and the head. This forms a very good fit 60 between the piston-head and the casing and effectually prevents any accidental leakage. An inlet-port a''' is placed in the casing A near its open end—that is to say, immediately behind the piston-head when the same is withdrawn to its farthest limit. This inlet-port allows the air to enter the pump, which is again forced outward through the nipple a' and into the tire when the piston is forced toward the head a.

To guide the piston B in its reciprocating motion, I have shown guiding-plates C C, secured to the casing in any suitable manner, and these plates are formed with faces c, conforming to the inner face of the casing. They 75 are also formed with guiding-faces c' c', parallel to each other and to the line of motion of the piston, the sides of which rest against the faces c' c' and are guided thereby. The plates C C are provided with shoulders c'', resting against the end of the casing and adapted to present a more finished appearance to the casing, but which also assists in keeping the guiding-plates in their proper positions.

Looking at Figs. 2 and 5, it will be seen that the piston B is provided with several compartments or chambers adapted to receive supplementary tools, such as are usually used in connection with bicycles, &c. The member b is enlarged considerably, as seen at d, and hollowed out to receive the shank D' of a wrench. The members b b' form the handle of a wrench K, and these members are connected by struts d' d'', in which is journaled a nut I, meshing with the teeth upon the shank D', and upon the shank D' is formed a jaw D, the transverse member d'' upon the piston forming the other jaw of the wrench. A third strut d''' connects the enlarged portion d of the member b with the member b', and in the opening between the struts d' d'' are removably secured a small screw-driver and wrench, (lettered E F, respectively.) As

seen in Fig. 3, this screw-driver and wrench are pivoted together by means of a small screw *e*, the member *F* being preferably provided with a slot *f*. The wrench *F* is intended for use on small nuts or upon nipples, such as are used upon the ends of the spokes, and when this wrench is turned at right angles to the screw-driver it forms a very good grasp, whereby the screw-driver may be used to great advantage. The strut *d*¹ is recessed, as seen at *d*⁴, (see Fig. 5,) and the strut *d*³ is notched at *d*⁵ and provided with a rotatable disk *d*⁶, adapted to retain the wrench and screw in their proper position. This disk *d*⁶ is loosely secured to the strut *d*³ by a suitable screw and is partly cut away, as seen at *d*⁷. The screw-driver and wrench are of sufficient size to conveniently rest in the recess *d*⁴ and notch *d*⁵, and when the flat side of the disk is turned toward the screw-driver the same may evidently be placed in the notch *d*⁵; but when the disk *d*⁶ is partially rotated it secures the screw-driver and wrench in place. The piston is also adapted to receive an oil-can, as seen at *G*. This oil-can is shown as one of a width to conveniently fit between the members *b* *b*' and of a thickness less than that of the piston in order that it may easily pass between the guiding-plates *C* *C*. The nozzle *g* of the oil-can when in position is seated in a funnel-shaped socket *H*, secured upon a spring-plate *h*, which is fastened to the piston in any suitable manner and preferably near the piston-head in order to give as much room as possible for the can. The end or bottom of the can is provided with a V-shaped groove *g*', seated upon a correspondingly-shaped tongue *d*⁸ upon the enlarged portion *d* and strut *d*³ of the piston, as seen in Fig. 5, and the force of the spring-plate *h* tends to hold the can in the proper place. When it is desired to use the can, it may be released from its supports by pressing upon the end adjacent to the tongue *d*⁸, thus forcing the spring-plate *h* back and allowing the end of the can to slip over the tongue. To replace the can, the nozzle is thrust into the funnel-shaped socket *H* and the end forced over the tongue until the V-shaped groove *g*' is seated upon the tongue *d*⁸.

It is evidently necessary that the supplementary tools shown herewith be of such size and shape to be placed within the piston and yet allow the same to be reciprocated within the casing *A* when inflating a tire.

It will be seen from the drawings and from the foregoing description not only that the pump cylinder or casing is flat and of the most desirable form for carrying in the pocket,

but also that the two jaws *D* *d*² of the wrench 60 at the outer end of the piston are of the same transverse section as the pump-cylinder, so that when the device is closed it is practically of uniform size throughout its entire length. Furthermore, the adjusting-nut *I* of the 65 wrench lies wholly within that part of the piston-rod which enters the pump-cylinder, so that when the device is not in use, but is closed for carrying in the pocket, all the working parts are within the pump-cylinder and 70 are hidden from view and protected.

It is evident from the description of this implement that it is to be used by bicycleriders, and it is essentially a pocket tool, and the various advantages which have been recited adapt it particularly for the special use 75 to which it is designed.

Having now described and explained the nature of my invention, what I claim as new, and desire to secure by Letters Patent, is— 80

1. In a pump-wrench, the hollow pump-body, a wrench-stem arranged to traverse the pump-body, a plunger secured to the end of the stem within the body, a fixed jaw and a movable jaw at the other end of the stem, and 85 a finger-piece for operating the movable jaw, the opening in the body through which the wrench-stem passes being large enough to permit the jaws and finger-piece to pass therethrough, whereby the said jaws and finger-piece can be housed within the pump-body to some degree, substantially as described.

2. In a device of the class described, the combination with a flat pump-cylinder approximately rectangular in transverse section, of a piston-rod sliding and guided in said pump-cylinder and provided at one end with a piston and at the opposite end with a transverse member adapted to serve as the stationary jaw of a wrench, a shank sliding 100 and adjustable in said piston-rod and provided with a terminal jaw adapted to coöperate with said transverse terminal member on the piston-rod, and a nut lying within the piston-rod and engaging the shank sliding 105 therein, the pump-cylinder being adapted to receive within it the entire piston-rod with the exception of said transverse terminal jaw, whereby when the parts are closed together the adjusting-nut is within the pump-cylinder 110 and covered and protected thereby.

In witness whereof I have hereunto set my hand this 16th day of March, 1896.

EMANUEL W. SWEIGARD.
